UNITED STATES PATENT OFFICE.

ROBERT C. LEPPERT, OF CHICAGO, ILLINOIS.

ACCORDION OR CONCERTINA.

978,460.

Specification of Letters Patent. Patented Dec. 13, 1910.

Application filed April 21, 1910. Serial No. 556,756.

To all whom it may concern:

Be it known that I, ROBERT C. LEPPERT, a citizen of the United States, residing at Chicago, in the county of Cook and State of Illinois, have invented certain new and useful Improvements in Accordions or Concertinas, of which the following is a specification.

This invention relates to improvements in accordions or concertinas, and it consists in certain peculiarities of the construction, novel arrangement and operation of the various parts thereof, as will be hereinafter more fully set forth and specifically claimed.

15 The principal object of the invention is to provide an accordion or concertina of such construction that the general efficiency of the instrument will be augmented by providing means for increasing its range, or in 20 other words, for producing more musical notes and combination of notes, than can be produced by the use of concertinas of the ordinary construction.

Another object of the invention is to provide a new and improved movement of the key-levers and of the valves which they carry, and operate, to the end that the ports or openings which said valves control will be opened and closed completely and quickly, 30 and not by degrees, or one part thereof at a time.

Still another object of the invention is to furnish simple, cheap and effective means for producing a smooth, undulating, trembling tone or tremolo when desired.

Other objects and advantages of the invention will be disclosed in the subjoined description and explanation.

In order to enable others skilled in the art 40 to which my invention pertains, to make and use the same, I will now proceed to describe it, referring to the accompanying drawings in which—

Figure 1, is a plan sectional view taken on 45 line 1—1 of Fig. 3, showing a portion of a concertina embodying the invention with the hand strap thereof omitted; Fig. 2, is an end view in elevation of one end of the instrument with the hand strap thereof omitted; Fig. 3, is a vertical sectional view taken on line 3—3 of Fig. 1, looking in the direction indicated by the arrows, showing the means for controlling one of the valves employed to change the course of the passage 50 of air to and from the reeds; Fig. 4, is a detail view in section of a portion of the box

of the concertina showing a part of the means for operating the air-controlling valve in another position from that shown in Fig. 3; Fig. 5, is an inner face view of the reed-box, chamber or compartment showing the means for controlling the passage of air thereto and therefrom; Fig. 6, is a vertical sectional view taken on line 6—6 of Fig. 5, looking in the direction indicated by the 60 arrows; Fig. 7, is a similar view taken on line 7—7 of Fig. 5, looking in the direction indicated by the arrows; Fig. 8, is a view in front elevation of the reed-board, showing the key-levers mounted thereon; Fig. 9, is a 70 fragmental view of the reed-board, the key-levers, and their valves being removed therefrom, and illustrating the brackets on which said levers are fulcrumed; Fig. 10, is an enlarged vertical sectional view of the reed- 75 board, showing the reed-boxes and key-levers mounted thereon, and illustrating by dotted lines some of the positions the parts will occupy in the operation of the instrument; and Fig. 11, is a fragmental sectional view 80 of the reed-board, showing the manner of constructing and arranging some of the key-levers thereon.

Like numerals of reference, refer to corresponding parts throughout the different 85 views of the drawings.

As the construction of concertinas is well known, and as my invention does not require the changing of the parts thereof, except the location of the tremolo boxes, I have 90 shown only enough of the instrument to illustrate the construction and operation of my improvements, and will describe only such parts as is necessary, to a proper understanding thereof.

The reference numeral 15, designates one 95 of the end boxes of the concertina which is provided as usual with reed-boxes 16, provided with reeds 17, of the ordinary construction, and with key-levers which are 100 fulcrumed on suitable brackets 18, secured on the outer surface of the reed-board 19, which is provided with openings 20, leading to the reed-boxes, and which openings are controlled by means of valves 21, mounted 105 on the key-levers 22, at one of their ends. These levers are extended horizontally in front of the reed-board 19, when the instrument is held in position for playing and have on their ends opposite the valves 21, 110 keys 23, extended through suitable openings in the key-board 24, as is clearly shown in

Fig. 2, of the drawings. As shown in Figs. 1, 8, and 10, the key-levers 22, which close the openings 20, on one side of the brackets 18, are held in their closed positions by means 5 of springs 25, secured at one of their ends on a rod 26, mounted at its ends on suitable brackets 27, secured to the outer surface of the reed-board. The key levers 22^a, 22^b, 22^c, the two latter of which carry valves 21, to 10 close openings 20, in the reed-board, are controlled by means of springs 28, which rest on the valved ends of said keys and are secured to a rod 29, supported at its ends on brackets 30, mounted on the outer 15 surface of the reed-board.

By reference to Figs. 10, and 11, of the drawings, it will be seen and understood that each of the key-levers 22^a, is provided near its fulcrum with a foot 31, which rests 20 on the ends of the key-levers 22^b, and 22^c, alternately, so that when the free ends of the levers 22^a, are depressed, the valves 21, on the levers 22^b, and 22^c, will be raised from the openings 20, which lead to the reed- 25 boxes 16. As the levers 22^a, which control the levers 22^c, are depressed, it is apparent that the levers 22^c, will be raised at their valved ends, in which operation the projections 32, on the outer surfaces of the valves 30 on the levers 22^c, will contact with the springs 28, and as the valves are secured to said levers by means of flexible pieces 33, such as leather disks, the said valves will be caused to move and instantly and completely 35 open the ports 20, which they control. The same operation will be performed with the key-levers 22^a, which control the levers 22^b, except that instead of the valves on the last-named levers being provided with projections 32, said projections are omitted and a rail 34, secured to the brackets 30, in parallelism with the board 19, will act as a stop 40 for the valves 21, on the levers 22^b, so as to hold them, and thus keep the openings 20, 45 completely exposed.

Secured to the box 15, which is at the melody end of the instrument, is a bellows 35, of the ordinary construction, which is united at its other end to the other box, not 50 shown, of the instrument. Located at the inner end of the box 15, is a partition 36, which is provided with an opening 37, for the passage of air to and from the reed chamber, which opening is closed by means 55 of a valve 38, hingedly connected at its upper end to the partition 36, above said opening therein. This valve may be provided with felt 39, to prevent rattling and to cause it to close the opening 37, more effectively. 60 On each side of the opening 37, the partition 36, is provided with an opening 40, and 41, around which openings are formed boxes 42, and 43, respectively, which boxes are inclined toward the partition 36, at their lower 65 and upper ends respectively, as is shown in

Fig. 6, of the drawings. Each of the walls 44, of said boxes, is provided with an opening 45, around which is secured a cushion 46, formed of sponge rubber, and each of said cushions has its free surface provided with a strip of felt 47. By reference to Fig. 6, it will be understood that the cushion 46, of the box 42, is secured around the opening 45, thereof within said box, while the cushion 46, on the box 43, is secured around the opening 44, thereof on the outside of said box. Each of the openings 45, in the boxes 42, and 43, is controlled by a valve 48, each of which is preferably provided on its surface adjacent to the cushion 46, with a flexible strip 49, which is secured at its upper end to a block 50, so that the valves may have free swinging movement. Connected to each of the valves 48, by means of a resilient piece 51, is a weight 52, which will vibrate 85 when the valves are closed suddenly and cause the instrument to produce tremolo sounds.

Extending through the upper portion of the key-board 24, is a push pin 53, which has 90 on its inner end an enlargement 54, to prevent it being moved outwardly too far. Extended longitudinally of the box 15, and from the enlargement 54, is a rod 55, which is supported by a bracket 56, secured to the 95 inner surface of the box 15, and has thereon, a disk 57, against which one end of a spring 58, coiled around said rod, rests, the other end of said spring resting against the reed-board 19. The inner end of the rod 100 55, impinges against a disk 59, on one end of a rod 60, which is supported on a bracket 61, secured to the inner surface of the box 15, and said rod has its other end pivotally connected to a lever 62, which is fulcrumed on the partition 36, and is adjustably connected at its lower end to the valve 38, by means of a screw 63. The valve 38, is connected by means of a spring 64, to the tremolo box 43, which spring normally holds said valve in 110 its open position, and the parts which control said valve in their normal positions as shown in Fig. 3, of the drawings, in which figure, as well as in Fig. 4, it will be seen that the push pin 53 is formed with a shoulder 53^a, to engage a plate 65, secured on the outer surface of the key-board 24, just below the opening therein, through which the push pin 53, is extended. By this arrangement, it will be seen that when the push pin 120 is pressed to the position shown in Fig. 4, the shoulder 53^a, will engage the plate 65, and hold the parts controlling the valve 38, in the positions shown in the last-named figure, so as to cause said valve to close the 125 opening 37, in the partition 36, which divides the reed-chamber from the bellows. The openings 37, 40, and 41, may be covered by means of a wire screen 66, so as to prevent the passage of dust or other foreign 130

substances into the instrument. The box 15, may be provided with a lever 67, having a connection 68, passing around a pulley 69, and connected to the valve 70, for the opening 71, for the intake of air. The instrument may also have the ordinary hand piece 72, and strap 73, therefor.

From the foregoing and by reference to the drawings, it will be clearly seen and readily understood, that by extending and retracting the bellows and operating the keys and lever controlling the intake of air, it will pass from the opening 71, into the bellows and from thence through the opening 37, in the partition 36, when the valve 38, therefor, is open, without producing any except the ordinary effect on the reeds, but by pressing the push pin 53, inwardly and through its connection with the valve 38, causing the same to close the opening 37, the air will be caused to pass through the openings 45, in the tremolo boxes 42, and 43, thus raising the valves 48, thereof, which, by reason of the weights 52, suspended therefrom by the vibratory pieces 51, will cause the instrument to produce tremolo sounds, and by reason of the sponge rubber cushions 46, said sounds will be smooth and undulating, and without the common mechanical effect. It is apparent that by causing the shoulder 53^a, on the push pin 53, to engage the plate 65, the opening 37, in the partition 36, may be kept closed for any desired length of time, thus continuing the tremolo sound, but when it is desired to discontinue such sound, the shoulder may be disengaged from the plate, when the springs 58, and 64, will restore the connections between the push pin 53, and the valve 38, as well as said valve, to their normal positions.

Having thus fully described my invention what I claim as new and desire to secure by Letters-Patent is—

1. In a concertina, the combination with an end box having reeds and keys, of a bellows secured to one end of the box, a partition located between the bellows and the reed

compartment and having openings therein, a box located around each of said openings and each provided with an opening in its wall opposite the partition, a sponge-rubber cushion located around each of the openings in said walls, and a vibratory valve to close each of said openings in the boxes and to rest on each of said cushions.

2. In a concertina, the combination with an end box having reeds and keys, of a bellows secured to one end of the box, a partition located at the juncture of the bellows with the box and having a plurality of openings therein, a pair of tremolo boxes mounted on the partition within the bellows, each of said boxes surrounding one of the openings in the partition and having an opening in its wall opposite the partition, a sponge-rubber cushion located around each of the openings in said walls, a vibratory valve adapted to coact with each of said cushions and to close each of the openings which they surround, a spring-actuated valve mounted to close an opening interposed between the first-named openings, the means connected to said valve to control the same.

3. In a concertina, the combination with an end box having reeds and keys, of a bellows secured to one end of the box, a partition located between the bellows and the reed compartment and having a pair of openings for the tremolo boxes and an opening between the same for the passage of air, a tremolo box located around each of two of said openings each provided with an inclined wall opposite the partition, each of said walls having an opening, a sponge-rubber cushion located around each of the openings in said walls, vibratory valves to coact with said cushions and to close the openings in the walls of the boxes, a valve to close the opening for the passage of air, and means to control said valve.

ROBERT C. LEPPERT.
